(No Model.)

L. DANNHAUSER.

UNDER GARMENT.

No. 298,832.

Patented May 20, 1884.

Witnesses:

James R. Bowen.
Alfred L. Brown.

Invensor:

Louis Dannhauser
By his attorney,
Edwin H. Brown.

UNITED STATES PATENT OFFICE.

LOUIS DANNHAUSER, OF NEW YORK, N. Y.

UNDER-GARMENT.

SPECIFICATION forming part of Letters Patent No. 298,832, dated May 20, 1884.

Application filed May 26, 1883. (No model.)

To all whom it may concern:

Be it known that I, LOUIS DANNHAUSER, of New York, in the county and State of New York, have invented a certain new and useful 5 Improvement in Under-Garments, of which the following is a specification.

My improvement consists in the combination, with a band provided with a section or sections of elastic material, of under-garments 10 severally provided with a draw-string and with means whereby they may be detachably secured to the band for the purpose of being supported thereby. By this combination of parts I can leave the garment or garments quite 15 loose, fasten the band tight about the waist, and still afford a great deal of freedom for the various evolutions of the body, owing to the yielding nature of the elastic section or sections in the band.

20 In the accompanying drawings, Figure 1 is a view of a petticoat embodying my improvement. Fig. 2 is a view of a pair of drawers embodying my improvement, and Fig. 3 is a view of a band embodying my improvement.

25 The petticoat and the pair of drawers severally lack a band, and have in lieu thereof draw-strings a, fitted in a pocket, b. Below the pocket in which the draw-strings are contained each garment is provided, as here 30 shown, with a number of eyelets, c. The band may be made, in the main, of any suitable woven material; but it is provided with a section or sections of an elastic material—such, for instance, as a loosely-woven fabric having strands of india-rubber incorporated into it. 35 This band is provided at intervals with hooks e, which may engage with the eyelets c of the garments before described. The ends of the band may be united by strings f, or by any other suitable devices.

40 By my improvement I not only enable one band to do service for a number of garments, but I render it practicable to leave the garments loose around the waist and to merely tighten the band, and then such a yielding 45 pressure will be exerted around the waist that it will not produce any discomfort.

Any other suitable devices may be substituted for the eyelets c and the hooks e, if desirable.

50 What I claim as my invention, and desire to secure by Letters Patent, is—

The combination, with a band provided with a section or sections of elastic material, of under-garments severally provided with a draw- 55 string and with means whereby they may be detachably secured to the band for the purpose of being supported thereby, substantially as described, whereby the band will act with a yielding pressure while the under-garments 60 may be left loose around the person.

LOUIS DANNHAUSER.

Witnesses:

T. J. KEANE,
ALFRED L. BROWN.